UNITED STATES PATENT OFFICE.

WILLIAM H. HONISS, OF HARTFORD, CONNECTICUT, ASSIGNOR TO FELIX W. LEINBACH AND CLARENCE A. WOLLE, BOTH OF BETHLEHEM, PA.

PAPER-BAG MACHINE.

SPECIFICATION forming part of Letters Patent No. 329,561, dated November 3, 1885.

Application filed June 16, 1884. Serial No. 134,994. (No model.)

To all whom it may concern:

Be it known that I, WILLIAM H. HONISS, of Hartford, Connecticut, have invented a new and useful Improvement in Paper-Bag Machines, of which the following description and claims constitute the specification, and which is illustrated by the accompanying sheet of drawings.

This invention relates to the former of that part of a paper-bag machine which continuously manufactures a tucked paper tube from a continuous roll of paper. That part of such a machine is elaborately shown in Sheets 3 and 4 of the drawings of an application for Letters Patent of the United States, for a new and useful paper-bag machine, filed in the Patent Office by William A. Lorenz and William H. Honiss, May 15, 1884, and is fully described in that application. Not all the features of that part of such a machine are shown in the drawings of this application; nor are all the features which are shown in these drawings described in this specification, because the present invention relates to one portion only of that part of such a machine.

Figure 1 in these drawings is a cross-section of the tucked paper tube above mentioned. Fig. 2 is a plan view of my new former and of the adjacent parts of a paper-bag machine.

Fig. 3 is a side view of the same. Fig. 4 is a cross-section on the line Z Z of Figs. 2 and 3.

A is the rectangular part of the former. Under it are the roll B, the roll C, and the pressing-roll D, all three of which are identical in construction, mode of operation, and function with the corresponding parts of the apparatus shown and described in the application of William A. Lorenz and William H. Honiss for Letters Patent of the United States for an improvement in paper-bag machines, filed on the same day with this application. E and F are plates placed respectively above and below the tucked paper tube being made. These plates are supported by the standards G and H, each standard sup-

porting one side of each plate, but having no other function. I and J are horizontal rollers placed, respectively, above and below the tucked paper tube being made. These rollers are supported by the standards K and L, and have journals turning in bearings in those standards.

M and N are rollers turning on vertical axes between the rollers I and J and the drawing-rolls O and P.

The mode of operation of this invention is as follows: The paper tube Q is formed into a rectangular shape around the rectangular former A in the same way substantially as in the apparatus shown in the said application of May 15, 1884. The drawing-rolls O and P continuously pull the paper tube off from the former A, and thence between the rollers I and J, and thence between the plates E and F, and thence between the rollers M and N, and thence between themselves, and in so doing the rectangular paper tube is reduced to the tucked form shown in Fig. 1. The plates E and F and the rollers I and J may all be omitted from this apparatus and a good result will still be obtainable. In that case the drawing-rolls O and P and the rollers M and N co-operate alone to reduce the rectangular paper tube to the tucked form desired.

I claim as my invention—

1. The combination of the rectangular former A, the drawing-rolls O and P, the rollers M and N, and the plates E and F, all constructed and operating together substantially as described.

2. The combination of the rectangular former A, the drawing-rolls O and P, the rollers M and N, and the rollers I and J, all constructed and operating together substantially as described.

WILLIAM H. HONISS.
